ATHLETIC SHOE

George L. Pierce and Nils H. Thorkelson, Brooklyn, N. Y., assignors to A. G. Spalding & Bros. Inc., Chicopee, Mass., a corporation of Delaware

Application March 19, 1948, Serial No. 145,215

Term of patent 14 years

(Cl. D7--7)

To all whom it may concern:

Be it known that we, George L. Pierce and Nils H. Thorkelson, each a citizen of the United States, both residing at Brooklyn, county of Kings, and State of New York, have invented a new, original, and ornamental Design for Athletic Shoes, of which the following is a specification, reference being had to the accompanying drawing, forming part thereof.

Figure 1 is a perspective view of an athletic shoe showing our new design.

Fig. 2 is a side view thereof.

Fig. 3 is a top view thereof.

The characteristic features of our design for an athletic shoe reside in the rear or back portion thereof consisting of an upper having a narrow heel strap merging at its ends, at a point rearwardly from the sole portion of the shoe, with the sides of an elongate instep portion of tubular configuration and a bottom strap portion extending from the bottom of the back of the tubular instep portion to the back of the heel

strap to provide an open heel portion, all substantially as illustrated on the drawing.

We claim:

The ornamental design for an athletic shoe, as shown and described.

GEORGE L. PIERCE.
NILS H. THORKELSON.
